Char-Gale Manufacturing Company, Minne-
apolis, Minn., a corporation of Minnesota

Application February 11, 1952, Serial No. 18,468

Term of patent 14 years

(Cl. D81—21)

To all whom it may concern:

Be it known that I, Nick J. Dovolis, a citizen of the United States, residing at Minneapolis, State of Minnesota, have invented a new, original, and ornamental Design for an Air Register, of which the following is a specification, reference being had to the accompanying drawing, forming a part hereof.

Fig. 1 is a view in perspective of an air register, showing my new design;

Fig. 2 is a vertical section, taken substantially on the line 2—2 of Fig. 1; and

Fig. 3 is a fragmentary section, taken on the line 3—3 of Fig. 1.

I claim:

The ornamental design for an air register, as shown.

NICK J. DOVOLIS.
